UNITED STATES PATENT OFFICE

117,456

DESIGN FOR A CONFECTION

George T. Parr, Minneapolis, Minn., assignor to Holiday Corporation, Minneapolis, Minn., a corporation of Minnesota

Application July 24, 1939, Serial No. 86,210

Term of patent 14 years

To all whom it may concern:

Be it known that I, George T. Parr, a citizen of the United States, residing at Minneapolis, county of Hennepin, and State of Minnesota,
have invented a new, original, and ornamental Design for a Confection, of which the following is a specification, reference being had to the accompanying drawing, forming part thereof.

fection showing my new design.

Figure 2 is a perspective view looking toward the top.

Figure 4 is a plan view looking directly down on the top.

I claim:

The ornamental design for a confection, as shown.

GEORGE T. PARR.
